ABACUS OR THE LIKE

Thomas L. Mathison, 53 Sugar Maple Road,
Levittown, N.Y.

Filed Apr. 9, 1964, Ser. No. 79,424

Term of patent 14 years

(Cl. D25—1)

FIG.2

FIG.4

FIG. 1 is a perspective view of the abacus showing my new design;

FIG. 2 is a front elevational view of the abacus in a position of use;

FIG. 3 is an end view of the abacus of FIG. 1;

FIG. 4 is a top plan view of the abacus of FIG. 2;

FIG. 5 is a vertical section through the abacus.

The dominant features of my design reside in the parts shown in full lines.

I claim:

The ornamental design for an abacus or the like, as shown and described.
